UNITED STATES PATENT OFFICE.

WILLIAM SCHUTTLER, OF CHICAGO, ILLINOIS, ASSIGNOR TO UNIVERSAL ARCH COMPANY, OF CHICAGO, ILLINOIS, A CORPORATION OF ILLINOIS.

LOCOMOTIVE ARCH BRICK.

1,420,764.

Specification of Letters Patent. Patented June 27, 1922.

Application filed August 18, 1917. Serial No. 186,903.

To all whom it may concern:

Be it known that I, WILLIAM SCHUTTLER, a citizen of the United States, residing at Chicago, in the county of Cook and State 5 of Illinois, have invented certain new and useful Improvements in Locomotive Arch Bricks, of which the following is a specification.

The present invention relates to a brick of 10 refractory material intended for use in connection with locomotive fire-boxes for the purpose of constituting a fire arch or baffle therein. The specific type of arch to which the present invention relates is known as the 15 two-tube arch, and the center bricks thereof, when assembled, are arranged in inverted V-formation between the water tubes.

The principal object of the present invention is to arrange an interlocking connection 20 between the abutting edges of the center or V-bricks, which will be flexible in its construction, allowing a secure and efficient interlocking connection between these bricks irrespective of the possible warped condition 25 of the arch tube or variations in the size of the bricks.

A further object of the invention is to arrange this interlocking connection so that the arch is capable of flexing under the influence 30 of contraction and expansion of the parts within the fire-box without breakage.

A further object of the invention is to provide an interlocking connection which will have a substantial surface engagement 35 between the parts forming the connection.

A further object of the invention is to so arrange this interlocking connection that the parts thereof will not readily become mutilated or broken in shipping or other handling 40 of the bricks.

A further object of the invention is to so arrange this connection as to eliminate to a great extent the danger of its burning out and allowing the bricks to fall.

The invention further consists in the features of construction and combination of parts hereinafter described and claimed.

In the drawings:

Figure 1 is a cross section through a portion 50 of a locomotive fire-box, showing the arch of the present invention in position;

Fig. 2, a plan view of a portion of said box, showing the arch in position; and

Fig. 3, a section along line 3—3 of Fig. 1, 55 with the interlocking connection on the center bricks shown, in elevation.

In the art to which the present invention relates, there is now known a type of baffle or arch used in conjunction with locomotive fire-boxes having two water tubes therein. 60 These arches are composed of center bricks and side bricks. The center bricks abut against one another and meet along the medial line of the fire-box and are arranged in inverted V-formation. It is necessary to 65 have some interlocking means for holding these center bricks in abutting engagement, owing to the vibration of the locomotive when in operation and the movements of the arch brick under the influence of ex- 70 pansion or contraction of the fire-box structure, and the present invention deals specifically with the method of interlocking the abutting edges of these center bricks to maintain them in engagement and at the 75 same time allow flexibility.

Referring now to the drawings, the device is shown in conjunction with a locomotive fire-box, the inner walls 4 of which are illustrated diagrammatically. Secured within 80 the fire-box, and extending therein in the usual manner, are water tubes 5. The arch or baffle is composed of side bricks 6 and center bricks 7. The side bricks, as shown, are of the inclined type and are each formed 85 with a groove 8 along one edge, which rests against a water tube, and are formed at the opposite edge with a flat face 9 adapted to abut against the side of the fire-box and have a full face engagement therewith. 90

The center bricks 7 are the portion of the structure to which the present invention relates. These bricks are similar in construction and each is formed along one edge with a groove 10, which is adapted to engage with 95 the outer periphery of a water tube. The opposite edge of the brick is formed with a hemispherical protuberance 11 adjacent one end of the edge 12 of the brick; and adjacent the other end of the edge 12 is formed 100 a hemispherical depression 13. As will be seen from the drawings, the depression is greater in area than the protuberance, the reason for which will hereinafter appear.

When these bricks are assembled in operative position within the fire-box, they appear as in Fig. 1, with the edge 12 of one brick abutting against the edge 12 of the other, and when so positioned, the protuberance 11 on one brick will set into the depression 13 on the other brick, and there is thus formed a semi-ball and socket joint ad-

jacent each end of the abutting edges of the bricks, making an interlocking connection between the bricks.

It is impossible in the manufacture of a clay product such as these bricks are composed of, to maintain absolute accuracy in dimensions, and it is therefore necessary that some leeway be given for inaccuracies. By means of the ball and socket interlocking connection between the bricks, it is obvious that they can have considerable latitude as to dimensions and yet obtain a good interlocking engagement between the abutting edges of the bricks. This is due to the rounded formation of the protuberance and depression, which allows an easy and smooth movement between the bricks, and this feature is further carried out by making the depression larger than the protuberance to permit of play.

It also happens that the water tubes within the fire-box will in some cases become warped. Under such conditions the abutting edges of the bricks will be placed in angular position to one another, as differentiated from extending parallel to one another and abutting close together, and when thrown thus out of parallel the abutting edges will become spaced apart for a portion of their distance which will weaken the interlocking engagement between the bricks. By means of the ball and socket joint of the present invention, the bricks are capable of adjusting themselves to such position as may be necessary owing to a warping of the tubes, and at the same time maintaining a firm and efficient interlocking connection between the parts.

The present form of connection is an interchangeable one, allowing all bricks to be made of a single pattern and eliminating the use of rights and lefts.

Furthermore, these bricks, being made of clay or similar refractory material, are of course more or less subject to breakage in shipping and other handling. In the case of a tongue and groove formed along the abutting edges, the walls of the groove or the body of the tongue are very liable to become chipped and broken in shipping or other handling. In the present invention, the hemispherical protuberance will withstand a large amount of rough handling without becoming broken, and the walls of the socket, extending along only a very small portion of the length of the brick, are therefore unlikely to be broken out. The brick is thus made strong and durable from the shipping and handling standpoint.

60 I claim:

1. A locomotive fire arch construction comprising bricks, each brick being formed along one edge to rest against a water tube, said bricks when assembled having their op-

posite edges abutting against one another 65 and forming an arch section of inverted V-formation, means for interlocking said abutting edges comprising a single hemi-spherical protuberance adjacent one extremity of the abutting surface of each brick, and a 70 single hemi-spherical socket adjacent the opposite extremity of said surface, the size of said socket being relatively small compared to the area of the surface on which it is disposed thereby avoiding the cutting 75 away of any substantial portion of the edge of the brick, the said protuberance on each brick fitting into the socket on the abutting brick whereby a joint of a ball and socket nature is formed adjacent each end of the 80 abutting edges of said bricks, and said sockets being of greater size than the said protuberances to allow of relative movement between the sections and permit free compensation for expansion and contraction, 85 substantially as described.

2. In an arch construction, the combination with a plurality of supports of bricks the ends of which are grooved to engage said supports, the adjacent ends of which are in contact 90 to form an arch, said bricks being of duplicate form and each of said ends being provided with a hemi-spherical protuberance and a hemi-spherical socket, the socket being of a size materially larger than the protuberance in order to provide for limited 95 freedom of movement of the abutting ends of the bricks, substantially as described.

3. In an arch construction, the combination with a pair of arch tubes of two rows 100 of bricks abutting in pairs, the bricks of each row being grooved to engage an arch tube, the combined width of the two rows of bricks being greater than the distance between the two tubes whereby the bricks comprising the 105 row are held in position by gravity, the abutting surfaces of each pair of bricks in said rows being provided each with a hemispherical projection, and a hemi-spherical recess, the recess being of greater diameter 110 than the projection said projections and recesses being adapted to cooperate when the bricks are placed in end to end relation, the greater size of the recesses permitting limited 115 relative movement between cooperating bricks, substantially as described.

4. In an arch construction, the combination with a plurality of supports, of bricks having ends formed to engage said supports and having adjacent ends in contact to form 120 an arch, said bricks being duplicate in form and each of said adjacent ends being provided with a hemispherical protuberance and a hemispherical socket forming ball and socket joints between said adjacent ends, 125 substantially as described.

WILLIAM SCHUTTLER.
